DUSTER DRESS

Otto Halbreich, 1350 Broadway, New York, N.Y.

Filed Oct. 18, 1962, Ser. No. 231,401

1 Claim. (Cl. 2—74)

This invention relates to women's garments and more particularly concerns a novel duster dress.

One object of the invention is to provide a duster dress for house wear which has a novel arrangement of panels and pockets.

Another object is to provide a duster dress having deep pockets extending all around the dress.

For further comprehension of the invention, and of the objects and advantages thereof, reference will be had to the following description and accompanying drawings, and to the appended claim in which the various novel features of the invention are more particularly set forth.

In the accompanying drawings forming a material part of this disclosure:

FIG. 1 is a front oblique view of the duster dress in open position.

FIG. 2 is a sectional view taken on line 2—2 of FIG. 1.

FIG. 3 is a rear oblique view of the duster dress in open position.

FIG. 4 is a fragmentary side view on an enlarged scale of the duster dress.

FIG. 5 is a fragmentary side view similar to FIG. 4 of another duster dress construction.

FIG. 6 is a sectional view similar to FIG. 2 of the duster dress of FIG. 5.

In FIGS. 1—4 is shown a duster dress having two generally rectangular front panels 12, 14 and two generally rectangular rear panels 16, 18. The front panel 12 is joined to rear panel 16 by longitudinal, vertical seam 20. The front panel 14 is joined to rear panel 18 by longitudinal vertical seam 22. At inner edge 24 of front panel 12 are spaced buttonholes 26. At inner edge 28 of front panel 16 are spaced buttons 30 which engage in the buttonholes respectively. A collar 32 extends around the upper end of the garment. Short sleeves 33^a, 33^b are secured to armholes 34^a, 34^b defined by upper lateral edge portions of the several panels. The sleeves have upturned cuffs 35.

The rear panels 16, 18 are joined by seams 37, 39 at their inner edges to a long narrow, central strip 21. Two narrower strips 23^a, 23^b have free lateral edges 24^a, 24^b extending the full length of the back of the dress and are attached at inner edges to seams 37, 39.

Two wide and deep rectangular pockets 40^a, 40^b are secured to the respective front panels 12, 14 on the outside thereof, intermediate their ends. Two other wide deep rectangular pockets 42^a, 42^b are secured to the rear panels on the outside thereof, intermediate their ends. The pockets 40^a and 42^a are joined at their outer edges to seam 20. The pockets 40^b and 42^b are joined at their outer edges to seam 22. Pockets 42^a and 42^b are joined at their inner edges to the rear panels by seams 37^a, 39^a. The pockets are all open at their straight upper ends and are closed and secured to the several panels by straight horizontal stitching 44^a, 44^b. The inner edges of the rear pockets are concealed between the free edges 24^a, 24^b of strips 23^a, 23^b and the rear panels.

In FIGS. 5 and 6 the duster dress 10^a omits the outer lateral seams of the pockets 40^a and 42^a. Pockets 40^a extends continuously from its front inner edge 50 at panel 12 around the dress to the rear panel 16 and rear inner edge 52 terminates between strip 23^a and panel 16. Pocket 42^a extends continuously from its front inner edge 51 at panel 14 around the dress to the panel 18 and inner

2

edge 53 terminates between strip 23^b and panel 18; see FIG. 6. Pockets 40^a and 42^a are not attached to seams 20^a, 22^a.

Pockets 40^a and 42^a are open at the top and have straight top edges 55 free from the panels. The bottom edges 56 are sewn by stitching 58 to the respective panels. The edges of the pockets can be trimmed with edging matching or contrasting with that of the panels and of strips 23^a, 23^b.

The garment construction described provides a novel arrangement of four pockets which extend around substantially the full circumference of the duster dress intermediate its ends. These pockets permit the user to carry numerous articles and implements used in performing household duties while wearing the duster dress. A further convenience is provided the user in having large pockets at the back and front. In addition, the duster dress may be worn in either of two ways, with panels 12, 14 facing to the front and panels 16, 18 facing to the rear or vice versa. Thus the wearer can change the appearance of the garment without changing its basic utility.

The duster dress described is one of general utility. It is attractive in appearance and inexpensive to manufacture.

While I have illustrated and described the preferred embodiments of my invention, it is to be understood that I do not limit myself to the precise constructions herein disclosed and that various changes and modifications may be made within the scope of the invention as defined in the appended claim.

Having thus described my invention, what I claim as new, and desire to secure by United States Letters Patent is:

A duster dress comprising a loose tubular body open at the ends and front, including four generally rectangular panels, an elongated central strip having opposite lateral edges respectively joined by seams to one lateral edge of each of a first two of said four panels, the other two panels each having one lateral edge joined by another seam to the other lateral edge of each of the first two panels, fastening means on free lateral edges of the other two panels for closing the front of the body, a first large deep pocket opening upward and extending around said body from a point adjacent one lateral edge of said strip across one of the first two panels and one of the other two panels and terminating near the free edge of the last-named one panel, a second large deep pocket opening upward and extending around said body from the other lateral edge of said strip across the other one of the first two panels and the other one of said other two panels and terminating at the free edge of the last-named other one panel, both pockets being free from the other seams, a pair of long narrow other strips at opposite edges of said central strip extending the full length thereof and concealing edges of the pockets thereat, said body having armholes at upper ends of adjoining edges of the panels, a pair of sleeves secured to the armholes at upper ends of adjoining edges of the panels, and a collar extending around the upper edge of each panel and of said strip.
